Patented Jan. 30, 1917.

FIG. 1.

FIG. 2.

VITNESS:

Robert A. Kitchell.

INVENTOR

Lars H. Bergman
BY

Frank J. Busse

ATTORNEY

UNITED STATES PATENT OFFICE.

LARS H. BERGMAN, OF PHILADELPHIA, PENNSYLVANIA.

PULVERIZED-FUEL BURNER.

1,213,821.

Specification of Letters Patent. Patented Jan. 30, 1917.

Application filed July 16, 1915. Serial No. 40,172.

To all whom it may concern:

Be it known that I, LARS H. BERGMAN, a subject of the King of Sweden, residing at Philadelphia, county of Philadelphia and State of Pennsylvania, have invented a new and useful Improvement in Pulverized-Fuel Burners, of which the following is a full, clear, and exact description, reference being had to the accompanying drawings, which form a part of this specification.

10 The invention relates to pulverized fuel burners for furnaces, boilers and kilns wherein air is employed both to atomize and propel the fuel and to effect combustion.

15 The main object of the invention is to so construct the burner as to require only one source of air supply. This object is effected by a construction in which the common supply of air is so divided that part thereof used for combustion is supplied either on the outside or on the inside of the stream of air employed for atomizing and carrying the fuel.

20 In this application there is set forth and specifically claimed an embodiment of the invention wherein air of comparatively high pressure is used and wherein the combustion air takes a path centrally within the stream of fuel atomizing and carrying air.

25 In an application of even date herewith, Serial No. 40,174, there is set forth and specifically claimed a construction wherein air of comparatively low pressure is used and wherein the combustion air takes a path centrally within the stream of fuel atomizing and carrying air. In an application of even date herewith, Serial No. 40,172, there is set forth and specifically claimed

30 a construction wherein the combustion air takes a path surrounding the passage for the fuel and atomizing and carrying air; the last-named application also claiming the subject-matter common to all arrangements.

35 In the present patent I have also claimed the subject-matter common to the present application and Serial No. 40,174.

In the drawings, which show a preferred embodiment of the invention, Figure 1 is 40 an elevation of, and Fig. 2 a vertical section through, the burner and fuel hopper.

The main pipe *f* of the burner has an inlet or hopper *b* connected to a pipe *a*, through which the fuel, fed thereto in 45 proper and uniform amount, by any known means, drops by gravity. The rear wall *c*

of the hopper is inclined downwardly and forwardly to distribute fuel over the cone *d*, the face of this cone *d* being located at a suitable distance in front of the vertical front wall of the hopper, forming a fuel delivery mouth *e*.

Pipe *f* is connected with a source of air supply provided with a damper *m* whereby the volume of air within the burner may be regulated. The forward part of pipe *f* is shown cylindrical, although it need not be so constructed, its form depending on the desired shape of flame. The inner pipe *g* dividing up the common source of air supply is made in a separate piece and is preferably shaped conical at the rear end. The inside face of cone *d* extends for some distance toward the rear of the burner, affording in connection with the conical shape of the rear of pipe *g* a gradually contracting passage for the atomizing and propelling air before it reaches the fuel delivered from the hopper, thereby causing the air at the forward end of cone *d* to build up a slightly higher pressure, insuring a maximum speed of air through the opening *a*. This opening is located at such a distance in front of the fuel hopper *b* that the inducing effect of the atomizing air will draw the fuel 85 through the fuel delivery mouth *e*.

The inner pipe *g* is arranged to slide longitudinally upon supports *j* on the inner wall of pipe *f*, its sliding movement being effected by means of rod *k*. By adjusting 90 the pipe *g* the area admitting the atomizing air may be increased or decreased, thus increasing or decreasing the volume of atomizing air to suit the varying amounts of pulverized fuel used in the furnace.

From the foregoing description it will be understood that the pulverized fuel is dropped through pipe *a* and hopper *b* and air under comparatively high pressure from a common source of supply is divided by 100 means of inner pipe *g* into two streams, one—the fuel atomizing and propelling air—passing within the annular space between the inner pipe and cone *d*, this space being so located in relation to fuel hopper *b* that 105 the inducing effect of the air draws the fuel through the fuel delivery mouth *e*, and conveys the fuel toward the discharge end of pipe *f*; while the other stream—the combustion air—goes through pipe *g*, entering the 110 furnace in the center of the fuel carried by the atomizing air.

Having now fully described my invention, what I claim and desire to protect by Letters Patent is:

1. A pulverized fuel burner comprising an outer pipe having a rear extension adapted for communication with a source of air supply, an inner pipe open at its rear end toward the forward portion of said rear extension of the outer pipe and adapted to receive and convey a portion of said air to effect combustion and affording between it and the outer pipe an annular passage, open at its rear, for another portion of said air to atomize and convey the fuel, and a fuel inlet to said passage in front of the rear end of the inner pipe. 70
2. A pulverized fuel burner comprising an outer pipe having a rear extension adapted for communication with a source of air supply, an open-ended inner pipe adapted to receive and convey a portion of said air to effect combustion and affording between it and the outer pipe an annular passage, open at its rear, for another portion of said air to atomize and convey the fuel, a fuel inlet to said passage in front of the rear end of the inner pipe, and means to vary the area back of the fuel inlet for admission of air to the annular fuel passage. 75
3. A pulverized fuel burner comprising an outer pipe having a rear extension adapted for communication with a source of air supply, an open-ended inner pipe adapted to receive and convey a portion of said air to effect combustion and affording between it and the outer pipe an annular passage, open at its rear, for another portion of said air to atomize and convey the fuel, a fuel inlet to said passage in front of the rear end of the inner pipe, and means to adjust the inner pipe to vary the area back of the fuel inlet for admission of air to the annular fuel passage. 80
4. A pulverized fuel burner comprising an outer pipe having a rear extension adapted for communication with a source of air supply, an inner pipe open at its rear end and adapted to receive and convey a portion of said air to effect combustion and affording between it and the other pipe an annular passage, open at its rear, for another portion of said air to atomize and convey the fuel, said inner pipe being tapered inwardly toward its rear, and a fuel inlet to said passage. 85
5. A pulverized fuel burner comprising an outer pipe having a rear extension adapted for communication with a source of air supply, an open-ended inner pipe adapted to receive and convey a portion of said air to effect combustion and affording between it and the outer pipe an annular passage, open at its rear, for another portion of said air to atomize and convey the fuel, said inner pipe being tapered toward its rear, a fuel inlet to said passage. 90
6. A pulverized fuel burner comprising an outer pipe having a rear extension adapted for communication with a source of air supply, an open-ended inner pipe adapted to receive and convey a portion of said air to effect combustion and affording between it and the outer pipe an annular passage, open at its rear, for another portion of said air to atomize and convey the fuel, and a fuel inlet to said passage in front of the rear end of the inner pipe, said passage tapering forwardly to the mouth of the fuel inlet. 95
7. A pulverized fuel burner comprising an open ended inner pipe, a surrounding outer casting forming with the inner pipe an annular passage for fuel atomizing and conveying air, a common air supply for both pipes, a fuel hopper, and a cone whose outer wall forms part of said fuel hopper and whose inner wall constitutes a part of the wall of said passage, there being a space between the front edge of the cone and the casting providing a mouth for the delivery of fuel from the hopper to said passage. 100
8. A pulverized fuel burner comprising an open ended inner pipe, a surrounding outer casting forming with the inner pipe an annular passage for fuel atomizing and conveying air, a common air supply for both pipes, a fuel hopper, and a cone whose outer wall forms part of said fuel hopper and whose inner wall constitutes a part of the wall of said passage, there being a space between the front edge of the cone and the casting providing a mouth for the delivery of fuel from the hopper to said passage, the rear part of the inner pipe tapering toward its rear end, it and the cone thereby affording between them a gradually narrowing passage for the atomizing and conveying air to said fuel delivery mouth. 105
9. A pulverized fuel burner comprising an outer pipe, an inner pipe inclosing a combustion air passage and affording between it and the outer pipe a passage for fuel and for fuel atomizing and conveying air, an inlet for air common to both pipes, and a fuel hopper communicating with the space between said pipes, said pipes being arranged to form a forwardly contracting annular passage, back of said fuel inlet, whose mouth is located in front of the front wall of the hopper. 110
10. A pulverized fuel burner comprising an outer pipe, a fuel hopper, an inner pipe inclosing a combustion air passage and affording between it and the outer pipe a passage for fuel and for fuel atomizing and conveying air, an inlet for air common to both pipes, the outer pipe having a conical portion whose front edge extends forward of 115
- 120
- 125
- 130

the front wall of the hopper and is spaced from the outer pipe to afford a fuel passage.

11. A pulverized fuel burner comprising an outer pipe having between its ends a conical portion spaced from the main wall of the pipe, a fuel hopper communicating with said space and whose front wall is back of the forward edge of said conical portion, an inner pipe inclosing a combustion air passage and affording between it and the outer pipe a passage for fuel and for fuel

atomizing and conveying air, part of the inner pipe within the conical portion of the outer pipe converging rearwardly and affording a forwardly contracting passage for the passage of air toward the fuel inlet, and an inlet for air common to both pipes. 15

In testimony of which invention, I have hereunto set my hand, at Philadelphia, on this 14th day of July, 1915.

LARS H. BERGMAN
